(57) **CLAIM**

The ornamental design of the light module, as shown and described.

DESCRIPTION

FIG. 1 is a perspective view of an embodiment of a light module;

FIG. 2 is a side view of the light module of FIG. 1; and, FIG. 3 is a plan view of the light module of FIG. 1.

The broken lines are provided for illustrative purposes only, and form no part of the claimed design. In addition, shadings are provided for illustrative purposes only, and do not form any portion of the claimed design.
